UNITED STATES PATENT OFFICE.

ERNEST O. FREDERICKS, OF NEW YORK, N. Y., ASSIGNOR TO E. FREDERICKS, INC., OF NEW YORK, N. Y., A CORPORATION OF NEW YORK.

ELECTRIC HEATER.

1,426,562.

Specification of Letters Patent. Patented Aug. 22, 1922.

Application filed August 2, 1921. Serial No. 489,211.

To all whom it may concern:

Be it known that I, ERNEST O. FREDERICKS, residing at New York, in the county and State of New York, have invented certain 5 new and useful Improvements in an Electric Heater, of which the following is a specification.

This invention relates to electric heaters, and more particularly to an electric heater 10 adapted for what is known as "permanent hair waving."

One of the objects of the invention is to provide a heater adapted for the above purpose, which is neat, compact, and of such 15 construction that the cables or leading-in wires are so attached to the heater that they do not interfere with the use of the latter, and are moreover, firmly attached to the heater.

20 Another object of the invention is to provide in a heater of the above type improved means for connecting the cables or leading-in wires with the resistance wire, which is employed as a heating element for the 25 heater.

Another object of the invention is to provide a heater of the above character, which is so constructed that there is extremely little 30 possibility of the same becoming deranged or disordered through use.

Other objects and aims of the invention, more or less specific than those referred to above, will be in part obvious and in part 35 pointed out in the course of the following description of the elements, combinations, arrangements of parts and applications of principles, constituting the invention; and the scope of protection contemplated will be indicated in the appended claims.

40 In the accompanying drawing, wherein I have shown a preferred form of embodiment of my invention:

Figure 1 is an elevational view of my improved heater.

45 Figure 2 is a view partly in elevation, and partly in section, showing the interior construction of the heater; and

Figure 3 is a view, partly in section and 50 partly in elevation, said view being taken at right angles to the position of the heater, as shown in Figure 2.

Similar reference characters refer to similar parts throughout the several views in the drawing.

55 Before proceeding with a description of

the construction of the heater, it may be here noted that it is of the utmost importance that the heaters employed in permanent hair waving be so constructed that there will be a minimum chance of their becoming inoperative or disordered in use, inasmuch as should a heater for instance become short-circuited while in operation upon the hair of the head of a human being, such short-circuiting will not only blow out the fuses, and 60 render all the devices inoperative, but there will be a great possibility of burning or otherwise injuring the hair being treated. To this and other ends, some of which will be mentioned in the course of the following description, I have designed my improved heater.

Referring now to the drawings, the reference numeral 1 denotes a cylindrically formed shell having an outer cylindrically formed shell or casing 2, said parts being 65 preferably spun or pressed together, as at 3 and 4, to provide a substantially integral structure.

Positioned upon the shell 1, is a layer of 70 insulating material 5, such for instance as mica, about which is wound the resistance or heating wire 6, the latter being preferably formed of one of the nickel-chrome alloys.

Before the resistance wire is wound about 75 the casing, however, there is provided at both ends, as at 7 and 8, of the casing, a plurality of windings of relatively strong wire, preferably brass, said wire being positioned upon the layer of insulating material, and the free ends of said wire being 80 twisted together, as at 9 and 10, so that the windings thereof are positioned tightly upon the casing and interposed insulating material.

Positioned upon the layer of resistance wire is a second layer of insulating material 11, so that the resistance wire is interposed between two layers of insulating material, the latter being preferably formed of sheet mica. Located exteriorly of said second 100 layer of insulating material is a sheet of insulating and heat resistance material 12, such for instance as asbestos, the construction being such that the twisted ends of the wires 7 and 8 lie between the heat resistance material 12, and the outer layer of insulating material 11, as clearly shown in Figure 3 of the drawing.

The resistance or heating wire 6 is at 110

tached to the wires 7 and 8 by being woven or zig-zagged across the latter, entirely around the circumference thereof, so that there are several points of contact between 5 said resistance wire and the fixed end wire.

This construction is of great advantage by reason of the fact that as hitherto constructed great difficulty has been experienced by connecting the leading-in wires with the resistance wires, inasmuch as the former is a 10 very strong construction, and the latter is a very fine wire, and any slight mechanical stress at the point of attachment, would disengage the parts at their points of connection, and render the heater inoperative.

The leading-in wires 13 and 14 extend within the space provided by the outer and inner shells and are twisted with the ends of the wires 7 and 8, to which tested ends the 20 ends of the resistance wires are also attached. The leading-in wire 14 it will be noted extends lengthwise of the space between the inner and outer shells exteriorly of the layer of resistance material 11.

25 Thus it will be seen that the leading-in wires are firmly attached to the wires 7 and 8; which are in effect circular terminals, and no mechanical stress whatever is put upon the resistance wire, which as above described, has at either end several points of electric contact with the said terminals 7 and 8.

Reference numeral 15 denotes the handle of the device, said handle being formed of a 35 metallic rod preferably forked shaped as shown, and also preferably offset as at 16 and 17, so that the offset end 18 is substantially parallel with the bore of the heater. The reference numeral 19 denotes the rod.

40 The cable 20 has one of its strands extending down each of the legs of the forked-shaped handle, and each strand is firmly bound to said legs and to the upper end 18.

Any suitable means may be employed to 45 fasten the strands of the cable to the legs and upper end of the metallic rod which forms the handle, such for instance as asbestos twine, or a plastic insulating composition may be employed in this relation, if 50 desired.

The rod which forms the handle is preferably anchored in the outwardly extending flange of the inner shell or cylinder 1.

It will accordingly be seen that I have 55 provided, among others, a construction well adapted to attain all the ends and objects above pointed out, in a very efficient manner. The heater is compact, and if desired, may be slightly tapered toward its lower end, 60 as at 21, so that a greater number of heaters may be used upon the head.

Having thus described my invention what I claim as new and desire to secure by Letters Patent is:—

65 1. In an electric heater, in combination, a

core member, a plurality of terminal members encircling said core, and insulated therefrom, one of said terminal members being positioned adjacent each end of said core, a resistance wire positioned about said 70 core, each end of said resistance wire having several points of contact with one of said terminal members, and a pair of leading-in wires, each of which is connected with one of said terminal members.

2. In a device of the class described, a cylindrically formed metallic shell, having a covering of insulating material positioned thereon, a plurality of wires wound about said shell, the opposite ends of each wire 80 being fastened to each other, each of said wires being positioned adjacent one of the ends of said shell, a resistance wire wound about said shell, each end of said resistance wire having several points of engagement 85 with said aforementioned wires, and a pair of leading-in wires, each of which is connected with one of said first mentioned wires.

3. In an electric heater, in combination, 90 a core member, a plurality of terminal members encircling said core and insulated therefrom, each of said terminal members being composed of one or more windings of relatively heavy wire, and one of said terminal members being located adjacent each end of 95 said core, a resistance wire positioned about said core, and at each end thereof having several points of contact with the terminal members, and a pair of leading-in wires, each of which is connected with one of said 1 terminal members.

4. In an electric heater, in combination, 1 a core member, a plurality of terminal members encircling said core and insulated therefrom, one of said terminal members 1 being positioned adjacent each end of said core, a resistance wire positioned about said core, each end of said resistance wire having several points of contact with one of 1 said terminal members, and each end thereof being connected thereto, a handle extending from said core, and a pair of leading-in wires fastened to said handle, and having their ends connected with said terminal.

5. In a device of the class described, a cylindrically formed metallic shell having a covering of insulating material positioned thereon, a plurality of relatively heavy wires wound about said shell, the opposite ends of each wire being fastened to each other so that each wire is permanently positioned upon said shell, and each of said wires being positioned adjacent one of the ends of said shell, a resistance wire wound about the insulating material upon said shell, said resistance wire adjacent each end thereof having several points of engagement with the aforementioned relatively heavy wires, a handle comprising a pair of legs joined at their upper ends, extending from

said shell, and a cable comprising a pair of leading-in wires, each wire of which is bound to one leg of said handle, each leading-in wire being connected to one of said relatively heavy wires, a covering of insulating material positioned upon said resistance wire, and a casing forming a covering for said shell, and the resistance wire and the insulating material mounted thereon.

10 6. In an electric heater, in combination, a core member, comprising a cylindrically formed shell, having a covering of insulating material positioned thereon, a plurality of wires wound about said shell and the insulating material thereon, adjacent each end thereof, the opposite ends of each of said wires being fastened together, a resistance wire, each end of which is disposed upon one of said first mentioned wires in zig-zag fashion; so as to have several points of contact therewith, and each end of said resistance wire being connected with one of said first mentioned wires.

7. In an electric heater, in combination, 25 a core member, comprising a cylindrically formed shell, having a covering of insulating material positioned thereon, a plurality of wires wound about said shell and the insulating material thereon, adjacent each end thereof, the opposite ends of each of said wires being fastened together, a resistance wire, each end of which is disposed upon one of said first mentioned wire in zig-zag fashion, so as to have several points of contact therewith, and each end of said resistance wire being connected with one of said

first mentioned wires, a handle comprising a pair of metallic legs joined together at their outer ends fastened to said core, and a cable comprising a pair of wires each of which is bound to one leg of said handle, each wire being connected to one of said first mentioned wires.

8. In an electric heater, in combination, a core member, comprising a cylindrically formed shell, having a covering of insulating material positioned thereon, a plurality of wires wound about said shell and the insulating material thereon, adjacent each end thereof, the ends of each wire being fastened to each other, a resistance wire, each end of which is disposed upon one of said first mentioned wires in zig-zag fashion, so as to have several points of contact therewith, and each end of said resistance wire being connected with one of said first mentioned wires, a handle comprising a pair of metallic legs joined together at their outer ends fastened to said core, and a cable comprising a pair of wires each of which is bound to one leg of said handle, each wire being connected to one of said first mentioned wires, a metallic shell fastened about said core and insulating material disposed between said shell, said resistance wire and said first named wires.

In testimony whereof I affix my signature in the presence of two witnesses.

ERNEST O. FREDERICS.
